FOLDING CHAIR

Russel Wright, New York, N. Y., assignor to Shwayder
Brothers, Ecorse, Mich., a corporation of Colorado

Application March 18, 1953, Serial No. 24,069

Term of patent 14 years

(Cl. D15—1)

Fig. 1

Fig. 2

Fig. 1 is a front perspective view of a folding chair, showing my new design;

Fig. 2 is a rear perspective view thereof;

Fig. 3 is a cross section, taken from front to rear, of the seat element of the chair;

Fig. 4 is a cross section of the seat element taken in the direction of the arrows 4—4 of Fig. 3 and with a portion of the seat broken away from convenience of illustration;

Fig. 5 is a perpendicular cross section of the back element of the chair; and

Fig. 6 is a cross section of the back element taken in the direction of the arrows 6—6 with a portion of the back broken away from convenience of illustration.

The instant application is a continuation-in-part of my earlier filed copending application, Serial No. D. 9,639, filed May 2, 1950, now abandoned.

I claim:

The ornamental design for a folding chair, substantially as shown and described.
